UNITED STATES PATENT OFFICE.

JAMES M. WHITNEY, OF SALEM, NEBRASKA.

STOVEPIPE-CLAMP.

SPECIFICATION forming part of Letters Patent No. 733,785, dated July 14, 1903.

Application filed February 24, 1902. Serial No. 95,485. (No model.)

To all whom it may concern:

Be it known that I, JAMES M. WHITNEY, a citizen of the United States, residing at Salem, in the county of Richardson and State 5 of Nebraska, have invented a new and useful Stovepipe-Clamp for fastening a Stovepipe in a Chimney, of which the following is a specification.

This invention relates to stovepipe-clamps, 10 and more especially to that class of devices for securing the pipe to the chimney, my object being to produce a clamp by which the pipe can be easily, quickly, and reliably secured in position, which is adjustable to accommodate chimney-walls of varying thickness, 15 which effectually prevents soot and smoke escaping into the room, and which is of simple, strong, durable, and cheap construction.

To this end the invention consists in certain novel and peculiar features of construction and combinations of parts, as hereinafter described and claimed, and in order that it 20 may be fully understood reference is to be had to the accompanying drawings, in which—

Figure 1 is a vertical section of a portion 25 of a chimney and of a pipe-clamp embodying my invention, the section being taken through the center of the clamp. Fig. 2 is a front 30 view of the clamp and of the chimney-pipe section detached from the chimney. Fig. 3 is a detached plan view of the locking-bar.

Referring to the drawings in detail, A designates a split clamp-band, of spring metal, 35 provided with substantially parallel ears connected by a stove-bolt C, a perforated locking-bar D being secured on said bolt between said ears and capable of vertical movement, as indicated by dotted and full lines, Fig. 1, 40 the perforations of said bar being arranged in longitudinal series, so that their axes shall extend substantially vertical when the bar occupies its operative or substantially horizontal position, as hereinafter explained.

F is the chimney-section of the stovepipe, 45 the same being fitted in the chimney-hole, as shown, and of length to project some distance into the room from the chimney, the band A being clamped tightly on said projecting portion by bolt C, with the band ears disposed vertically above the center of the pipe, the 50 customary collar E fitting snugly upon the

projecting end of the pipe between the band and the inner face of the chimney.

B designates a substantially U-shaped 55 clamp-bar extending through the chimney-hole above the pipe and also through the collar and between the ears of the band, one of the arms of said clamping-bar being disposed within the chimney flue or passage and the other forward of the inner end of the pipe.

To secure this pipe-clamp in position, the clamp-bar is first rotated so that its arms shall be pendent to permit the pipe-section, with the band and collar on its outer end, to be 65 slipped into the chimney-hole until the rear arm of the clamp-bar is disposed within the chimney flue or passage, and the collar is pressed by the clamp-band snugly up against the face of the chimney. The operator then 70 with one hand causes the perforated locking-bar to assume about the position shown in dotted lines, Fig. 1, and with the other rotates the clamp-bar until its arms project vertically upward. He then draws said clamp-bar forward until its rear arm bears snugly against the front wall of the chimney, as shown by dotted lines, Fig. 1, and while holding it in this position he lowers the locking-bar and causes the engagement of one of its holes 75 with the forward arm of the clamp-bar, and thereby clamps the pipe-section immovably and reliably in the chimney. To remove the pipe-section for the purpose of taking the stovepipe down, the locking-bar is disengaged 80 from the front arm of the clamp-bar. The latter is then pushed inward slightly, so as to remove it from frictional contact with the wall of the chimney, and is turned downward until its rear arm lies wholly within the plane of the 85 chimney-hole. The entire device can then be withdrawn from the hole.

From the above description it will be apparent that I have produced a stovepipe-clamp which embodies the features of advantage enumerated as desirable in the statement of invention and which may obviously be modified in some particulars without departing from its spirit and scope or sacrificing any of its advantages.

Having thus described the invention, what I claim as new, and desire to secure by Letters Patent, is—

1. A pipe-clamp, comprising a pipe-section,

- a clamp-band thereon, a clamp-bar on the pipe and bearing a sliding relation to the clamp-band, and a locking-bar carried by the clamp-band to engage the clamp-bar.
- 5 2. A pipe-clamp, comprising a pipe-section, a clamp-band thereon, a clamp-bar also upon the pipe-section and provided with an arm adapted to occupy the chimney flue or passage and to engage the front wall thereof, and a locking-bar carried by the clamp-band and engaging the clamp-bar to hold its arm against the chimney.
3. A pipe-clamp, comprising a pipe-section, a clamp-band thereon, a clamp-bar also upon the pipe-section and provided with an arm adapted to occupy the chimney flue or passage and to engage the front wall thereof, and a perforated locking-bar carried by the clamp-band and engaging the clamp-bar to hold its arm against the chimney.
4. A pipe-clamp, comprising a pipe-section, a collar thereon, a clamp-band also thereon forward of the collar, a clamp-bar upon the pipe-section and provided with an arm adapted to be disposed within the flue or chimney passage, and having a sliding relation with the clamp-band, and a locking-bar carried by the clamp-band and adapted to engage and lock the clamp-bar against movement.
- 25 5. A pipe-clamp, comprising a pipe-section, a collar thereon, a clamp-band also thereon forward of the collar, a clamp-bar extending longitudinally of and upon the pipe-section and through the collar and clamp-band, and adapted for rotatable and longitudinal adjustment and provided with an arm at its rear end, and a locking-bar carried by the clamp-band and adapted to engage and lock the clamp-bar in the desired position.
6. A pipe-clamp comprising a pipe-section, a collar thereon, a clamp-band also thereon forward of the collar, a clamp-bar extending longitudinally of and upon the pipe-section and through the collar and clamp-band and provided with an arm at each end, and adapted for rotatable and longitudinal adjustment, and a perforated locking-bar carried by the clamp-band to engage the front arm of the clamp-bar.
7. In a stovepipe-fastener, the combination of a stovepipe-section adapted to fit in the chimney-hole, a U-shaped clamp-bar adapted to extend through said chimney-hole and to have the inner end thereof rest against the side of the chimney-flue, and a hinged locking-bar adapted to be secured to the stovepipe-section, said locking-bar being provided with perforations to receive the outer end of said clamp-bar, by which said stovepipe-section may be secured in position.
